CONTROLLER GRIP FOR FORK LIFT TRUCKS OR THE LIKE

David De Witt Tompkins, Columbus, Ohio, assignor to
Crown Controls Corporation, New Bremen, Ohio

Filed Sept. 1, 1972, Ser. No. 285,757

Term of patent 14 years

Int. Cl. D13—03

U.S. Cl. D26—13 R

FIG-1

FIG-2

FIG-3

FIG-4

FIG-5

FIG-6

FIG. 1 is a perspective top view of the controller grip for fork lift trucks or the like;

FIG. 2 is a top view thereof;

FIG. 3 is a bottom view thereof;

FIG. 4 is a side elevational view thereof;

FIG. 5 is an end elevational view thereof; and

FIG. 6 is an end elevational view thereof opposite to that shown in FIG. 5.

I claim:

The ornamental design for a controller grip for fork lift trucks or the like, substantially as shown.
